HEATING AND VENTILATING APPARATUS

Herman A. Pietsch, Greentree, Pa., assignor to
Dravo Corporation, Pittsburgh, Pa., a corpora-
tion of Pennsylvania

Application May 12, 1942, Serial No. 442,615

1 Claim. (Cl. 236—1)

1

This invention relates to ventilation, and consists in apparatus for heating to a uniform and predetermined temperature a stream drawn from the open air where temperature is variable and unpredictable in value. The invention finds practical application in the ventilation of the chambers and spaces within buildings and industrial plants, where fumes injurious to equipment or noxious to workmen are generated.

In the accompanying drawings Fig. I is a view in vertical section of a particular installation of the apparatus of the invention; Fig. II is a view to larger scale, in vertical and transverse section, on the plane indicated at II—II, Fig. I. Figs. III and IV are fragmentary views to yet larger scale, on the horizontal planes severally indicated in Fig. II by the lines III—III and IV—IV. Fig. V is a wiring diagram.

In a vertical wall 50, that may be understood to be the outer wall of a building, a window opening is formed, and in the opening is conveniently set a bank 51 of louvre slats. Within the building an air box 52 is mounted. To this box atmospheric air, entering through the window opening, has free access. From the box a conductor 54 leads; and fans 53, arranged within the box, induce flow and drive a stream of air through the conduit 54 to the desired place of emergence into the room to be ventilated. Athwart the stream, and, as here shown, at the otherwise open intake end of the air box 52 a skeleton burner 55 extends. The burner is submerged in the stream of air that the fans impel; the air flows around the burner and passes intimately over all its ramifications.

In the sectional view, Fig. I, two fans 53 appear. There are in this installation four fans in all, standing as in Fig. I they are shown to stand. They are grouped in square assembly, and, as seen in Fig. I they stand aligned two by two in the line of sight.

As best seen in Fig. II, the burner here consists of a plurality of elongate loops 56 of pipe perforated throughout all the extent of the loop and on the down-stream side (relatively to air flow) with multitudinous orifices. From these orifices flames spring and burn freely in the air stream that flows with little disturbance over the loops. These loops 56 (in this case fourteen in number) are arranged in two banks, symmetrical with respect to the vertical mid plane through the air box. The loops of the two banks are oppositely arranged, pair by pair. The elaborate skeleton or open gridwork burner is functionally sectional, and, section by section, it may be brought into and taken out of operation. The burner is fed

through a gas supply pipe 57. Comparing Figs. II and III, it will be seen that valves 14 set in leads 570 from pipe 57 control gas flow to the loops, pair by pair. This is the case with all of the paired loops, excepting only the central pair in the succession. These are distinguished in the drawings by the numerals 560. With respect to that central pair, and as shown in Fig. IV, two valves 14 are provided, and they are set in the leads to the two loops severally. Thus it is possible, by proper control of the valves 14, to bring into service a single loop of the burner or any multiple of a single loop, up to full capacity—that is to say, in this case, up to fourteen loops.

15 The supply pipe 57 extends vertically and centrally between the two banks of loops. At the opposite ends of the banks pilot burners 58 are arranged. These pilot burners consist of orificed lengths of pipe that extend vertically adjacent the ends of the loops 56. The pilot burners are fed through the branch 59 from the supply pipe 57. Fig. II gives the structural appearance of the assembly, and shows the pipes 58 to be structurally united to the loops 56. It will, however, 20 be understood that the union here is structural only; and that there is no passageway for gas between the pipes 58 and the loops 56.

The burners are refined in structure, as the art knows, to afford practically complete combustion, 25 with the production of carbon dioxide and water vapor.

In the gas supply line are set (Fig. II) a pressure regulating valve 23, a shut-off valve 10, and a pneumatically operated control valve 17. The 30 pressure regulating valve 23 is effective, that, under varying pressure at the source, the gas shall reach the burners at a pressure not exceeding a pre-determined maximum. A by-pass around the control valve 17 is provided with a 35 pressure-regulating valve 24. In the branch 59, through which the pilot burners are fed, are set a pressure-operated switch 6, and a shut-off valve 8.

40 Spark-plugs 9, 9, assembled with the essential ignition transformers or induction coils, are provided for lighting the pilot burners 58, and flame units 20, 21 are associated, one with each spark plug and its ignition transformers.

In the entering stream of cold air is arranged 45 a remote bulb-thermostat 4 of the mercury-switch type. The bulb is subject to the temperature of the incoming fresh air. In the on-flowing stream of heated air is arranged a thermostat 5 of like character.

50 A control system is provided that is effective

2

in these particulars: (1) The heater is brought into operation by manual intervention; it continues in automatic operation, with adaptation to varying conditions, within a permissible range of variation. Should, however, such range be exceeded, the heater goes out of operation, and can be brought into operation again only by manual intervention. (2) In case the temperature of the incoming air exceeds a predetermined value; or in case the temperature of the heated air exceeds a predetermined value, the heater will go out of operation. (3) The manual intervention that brings the heater into operation consists, first, in the energizing of the fans, and second, in the opening of the valve 10 in the gas supply line. The fans set in motion sweep the air box clean of any accumulation of gas before any other part of the organization comes into action. When the fans have continued in action for an initial short but sufficient interval of time, a push-button may be pressed that controls further operation. The induction coils of the spark-plugs are then automatically energized; gas is automatically allowed to flow to the pilot burners; and the pilot burners are automatically lighted. When these preliminary operations have occurred the control valve in the main gas supply line is released, so that it may be opened. This valve then is opened manually, and the heater is brought into action. Meanwhile, the ignition transformers, their purpose served, are automatically de-energized. The opening of the control valve in the main supply line causes the loops of the burner to be lighted from the pilot burners, and, according as the temperature of the entering air is high or low, few or many of these loops will be brought into play. (4) As temperature conditions change, the number of loops that are brought into play increases and diminishes, and, when any number of the loops are active and when conditions are in state of change, so as to bring about increase or diminution of the number of loops in action, the volume of the supply of gas to the loops will increase or diminish. Thus, minute gradation is afforded in the increase or decrease of the rate of heat generation. (5) In case gas pressure fails to a dangerous minimum the heater will automatically go out of operation. (6) In case the out-of-doors temperature becomes so warm that heating is unnecessary, the heater will automatically go out of operation. (7) In case the temperature of the delivered air rises to a degree exceeding a predetermined maximum, the heater will automatically go out of operation. And in any case, when once the heater has gone out of operation, operation can be renewed only through manual intervention.

The control apparatus is advantageously mounted on a panel 16 within a control room 60. Its parts are shown diagrammatically in Fig. V in organization with the heater parts. Electric energy is taken from service line 61; and pneumatic power is supplied at 62. In Fig. V the electric circuits are indicated in full lines; the pneumatic connections in heavy dotted lines.

Operation, of which a summary has already been given, is now repeated in detail, and with reference to the drawings—particularly to Fig. V.

The fans are set in operation by the manual shifting of the switches 18. The shifting of the switches effects the closing of the corresponding contacts of relays 2. This particular installation is so arranged that it is only in sequence upon

the operation of at least two of the fans that the heater can be brought into operation, and to such end the relay contacts are wired, as indicated in the diagram. When at least two of the fans have continued in operation for a predetermined time interval, in this case three minutes, the purge timer 3 becomes effective. The purge timer is a delayed action switch. Several types are available on the market, and the one here employed includes a resistance element that is slowly distorted under the effect of an electric current, and that is, after a predetermined interval of time, effective to close the switch contacts. The push button 1 may then be pressed with effect.

When the push-button 1 is pressed circuit is completed through relays 7, 7, to the solenoid that controls valve 8 in the branch line 59 that supplies gas to the pilot burners, and to the induction coils or ignition transformers of spark-plugs 9, 9. Thereupon the pilot burners are lighted. Flames projected by the pilot burners play upon the two electrodes 20, 21, and in so doing complete circuits that energize additional units within relays 1, 1. These units, so energized, are effective, both to break the circuits through which the coils of the spark-plugs 9, 9 have been energized (so that the spark plugs now go out of action), and to complete a circuit that effects the shifting of a latch upon valve 10, releasing the valve to respond to manual operation. The relays 1, 1, spark-plugs 9, 9, and electrodes 20, 21 form the essential elements of a known piece of apparatus that is supplied by The Brown Instrument Company of Philadelphia, Pennsylvania, under the trade name Brown Protectoglo.

Pneumatic pressure, entering at 62, has access, through controller 12 and electrically operated pneumatic switch 11, to switches 13. Maximum pressure exerted upon switches 13 closes all circuits and opens all valves 14 and maximum pressure effects the opening to the full of valve 17 also.

When valve 10 is opened the burner lights itself from the already lighted pilots; and as the burner continues in operation the air in the fan-impelled stream is heated. The thermostat bulb 12a in the line of stream flow responds to the rising temperature, and effects a corresponding response in an air valve in controller 12.

The controller 12 is an instrument known to the art, available under the trade name Air-O-line Potentiometer Controller from The Brown Instrument Company, above mentioned. Suffice it to say that the pneumatic pressure in the air line extending from the controller is temperature governed; that the controller is so organized as to afford to the switches 13 pneumatic pressure that ranges from zero to fifteen pounds. The actual value depends upon and accords with the temperature of the stream of heated air that flows from the burner. At zero pressure the control valve 17 is closed, all the pneumatic-electric switches 13 are de-energized, and all the solenoid valves 14 are closed; at a pressure of fifteen pounds, all are open. The pneumatic-electric switches 13 are set to respond severally to different degrees of pressure; and, when the pressure afforded by the controller 12 is intermediate in value, a portion only of the switches 13 will be energized and a corresponding portion of the solenoid valves 14 will be open. As the temperature of the delivered stream of heated air varies, particular valves 14 will open and close,

so as to afford correspondingly varying volumes of flame in the burner.

The degree of opening of valve 17 is in general accord with the number of valves 14 that are open and the number of burner loops that are active; and valve 17 has this further value and effect, that it corrects or graduates what otherwise would be a step-by-step augmentation and diminution in the quantity of heat units released at the burner. As the pressure changes, causing increase or diminution in the number of burner loops currently active, the simultaneous shifting of valve 17, increasing or decreasing the gas flow, makes compensation, prevents the step-by-step effect alluded to, and affords instead an evenly graduated augmentation or diminution in the heat release.

The thermostat 5 includes a mercury switch. When the maximum predetermined temperature has been attained, this switch, normally closed, is opened. The opening of the switch in element 5 effects the opening of the circuit of the electrically operated pneumatic switch 11. When this circuit is opened the air line is bled, pressure fails in the pneumatic line, all the switches 13 are de-energized, all the valves 14 close, and valve 17 closes.

Similarly when the temperature of the outside air rises to a degree at which heating is unnecessary and undesired the thermostat 4 is effective to close all valves 14 and the valve 17 also.

When the pressure of the gas supply fails and reaches a critical minimum, the pressure switch 6 (here conveniently arranged in the branch line 59) opens a circuit with the same effect—the operation of switch 11, and the consequent loss of pneumatic pressure and the closing of all valves.

Fig. V shows the three switch members 4, 5, and 6 to be included in series in a single circuit. All three switches are normally closed. The opening of any one results in the opening of the circuit of switch 11.

Failure of the flame of either of the pilot burners breaks a flame circuit through the corresponding relay 7. In consequence, all circuits are

opened, both of the valves 8 and 10 close, valve 17 closes, and all the valves 14 close.

When the valves have closed the fans will continue in operation until their switches 18 are manually shifted.

I claim as my invention:

In a direct-fired heater system where gas fuel is burned in a duct through which air to be heated is circulated, the combination with a duct and means for circulating a current of air through the duct, of a plurality of gas burners in the duct, a common gas supply line and manifold for all of the burners, a modulating valve means in the supply line operable to gradually increase and diminish the supply of gas to the burners, a separate valve between each burner and the manifold for individually controlling each burner, means for progressively opening or closing the last-named valves in predetermined order to selectively vary the number of burners in operation, and means for operating the modulating valve to gradually increase or diminish the supply of gas to the burners then in operation whereby the temperature of the air being heated may be modified through a substantially uniform gradient as burners are progressively rendered operative or inoperative.
